Attorney.

UNITED STATES PATENT OFFICE.

WILLIS A. GOODWIN, OF KIRKSVILLE, MISSOURI.

SAND-CLEANING MACHINE.

1,425,763.

Specification of Letters Patent. Patented Aug. 15, 1922.

Application filed April 2, 1921. Serial No. 458,142.

To all whom it may concern:

Be it known that I, WILLIS A. GOODWIN, a citizen of the United States, residing at Kirksville, in the county of Adair and State 5 of Missouri, have invented certain new and useful Improvements in Sand-Cleaning Machines, of which the following is a specification, reference being had to the accompanying drawings.

10 The present invention has for its purpose to provide a machine of this character, wherein a screw conveyor or auger is employed on an inclined plane mounted in a trough or chute including means for feeding water at intervals at one side of the trough or chute, whereby the sand may be propelled through the chute or trough against the water, which washes it, the sand being carried upwardly and discharged into 15 a wagon, while the foreign matter or dirt and water discharges at the lower end on the ground.

20 Another purpose is the provision of means for sifting the sand, separating the larger parts, such as gravel and large stone, prior to feeding it into the chute.

25 Still another purpose is the provision of means for shaking or vibrating the sieve, and also having operative connections with the conveyor for imparting movement to the auger, whereby the process of cleaning the sand is substantially continuous.

30 A further purpose consists in the provision of means for swivelly connecting the chute and the shaft of the conveyor, to permit the chute to be raised and lowered, in order to change the inclination of the same, in combination with means for tilting the chute.

35 40 A still further purpose is the provision of means for regulating the pump, so as to govern the supply of water being fed to the chute.

While the design and construction at present illustrated and set forth is deemed preferable, it is obvious that as a result of a reduction of the invention to a more practical form for commercial purposes, the invention may be susceptible of changes, and 45 the right to these changes is claimed, provided they are comprehended within the scope of what is claimed.

The invention comprises further features and combination of parts, as will be here-

inafter set forth, shown in the drawings and 55 claimed.

In the drawings:

Figure 1 is a plan view of the improved sand cleaning machine constructed in accordance with the invention.

Figure 2 is a view in side elevation of the same.

Figure 3 is a sectional view on line 3—3 of Figure 1.

Figure 4 is an enlarged detail view in elevation of the pump mechanism and means for controlling the same.

Figure 5 is an enlarged detail view of the ratchet mechanism for the shaft 39.

Figure 6 is a detail view of a screw conveyor shaft 29^a with the spiral screw blade carried thereby and in sections.

Figure 7 is a detail sectional view through a portion of the conveyor shaft 29, showing the mounting of one of the sections on the 75 shaft.

Referring to the drawings, 1 designates a frame, which may fit the wagon, so that it may be moved from one place to another, though it is obvious the frame may be supported stationary.

Mounted on the frame 1 is a suitable sieve 2 having sides 3, in which the sand to be cleaned may be deposited. The sieve is supported by the uprights 4 which are 85 hinged at 5 and 6 to the sieve and the sides of the frame 1. It will be noted that these supports 4 are capable of being oscillated, therefore causing an oscillatory movement to be imparted to the sieve. A hopper 7 90 extends downwardly from the sieve, and has inclined sides, and terminates in a chute 8. It will be noted that the upper and lower ends of the uprights 4 are beveled. The bevels of the uprights 4 on the left in 95 Figure 2 are inclined correspondingly, while the bevels on the ends of the uprights 4 at the right are beveled correspondingly in the opposite direction. These bevels permit the uprights 4 to tilt, when a reciprocating movement is imparted to the sieve 2.

Furthermore the bevels of the uprights 4 on the left in Figure 2 contact with the side pieces of the frame 1, and the bottom of the sieve 2, thereby limiting the sieve when 100 reciprocated in one direction. The bevels of the opposite uprights 4 will limit the sieve 105 when reciprocated in the opposite direction.

Furthermore it is obvious that should the pitmen 14 be disconnected from the cranks of the shaft 9, the uprights 4 will act to support the sieve, and will not allow it to collapse entirely in engagement with the frame 1. For instance one set of bevels or the other will cooperate with the frame 1 or the sieve, and support the sieve, thereby preventing the chutes 8 and 15 from being 10 damaged, by contacting with some object or with some part of the machine. For instance should the sieve tilt in a direction toward the chute or trough 21, in case the pitmen 14 are disconnected from the crank 15 shaft, the chute 8 would bear or engage into the chute or trough 21, and may in all probability damage some part of the machine. However due to the construction of the uprights 4, the sieve may at all times be supported, out of contact with the frame of the machine below.

A crank shaft 9 is mounted in bearings 10 of the frame 1 and has pulleys 11 on its ends. An additional pulley 12 is also carried by the 25 shaft 9. The cranks 13 of the shaft are operatively connected by the pitman 14 to the sieve, in order to impart an oscillatory movement thereto. A downwardly inclined trough 15 is carried by the sieve, for the 30 purpose of carrying off all rocks and large pieces, which do not pass through the openings of the sieve. The rocks and large pieces are discharged through the openings 16.

35 A second shaft 17 is mounted in bearings of the sides of the frame 1, and pivotally mounted on this shaft by means of the bearings 18 are beams of connecting pieces 19, which are bolted at 20 to the sides of a 40 chute or trough 21, thereby pivotally mounting the chute or trough 21, so that it may be tilted upwardly and downwardly. The ends of the shaft 17 carry pulleys 22, which are operatively connected to the pulleys 11 by 45 means of belts 23, though it is obvious that either one of the belts may be dispensed with if desired. By means of a pulley 24 operatively connected to any suitable source of power by means of a belt 25, power may be 50 transmitted to the crank shaft 9, which will in turn impart movement to the shaft 17.

A bevel gear 26 is carried by the shaft 17, and in mesh with gear 27, which is carried by the shaft 28 of the screw conveyor or auger 55 29, which is mounted in the chute or trough 21. The shaft 28 of the screw conveyor or auger is mounted in bearings 30 of the cross pieces at the ends of the chute or trough 21. The shaft 28 is also mounted in a bearing 31 60 which is carried by the cross piece 32, which connects the beams or pieces 19. Suitable collars 33 are mounted on the shaft 17, to hold the beams or pieces 19 in position, and thereby hold the gears 26 and 27 in mesh. 65 By this construction it will be noted that the

chute or trough 21 is swivelly mounted, yet the shaft 28 receives revoluble movement, allowing the chute or trough to be tilted upwardly and downwardly, so as to regulate the travel of the sand.

70 A derrick 34 is mounted upon the frame 1, and journaled upon a shaft 35 of the upper part of the derrick is a pulley 36, which is engaged by a cable 37. One end of the cable 37 is operatively connected to the chute or trough 21 as shown, while the other portion of the cable is wound about a drum or reel 38, which is rotatable with the stub crank shaft 39, there being a ratchet and pawl 40 and 41 for holding the reel or drum in different positions. Obviously by turning the crank shaft 39, the cable 37 may be wound upon the reel or drum, and thereby tilt the chute or trough, to different inclined positions for governing 85 the travel of the sand.

Also carried by the frame 1 is a conventional form of pump 42, which obtains the supply of water through the pipe 43, which may be connected to any suitable source of 90 supply. A pipe 44 is connected to the pump and is extended and terminates in a portion 45, which is disposed in parallelism to the chute or trough 21. The portion 45 of the pipe is provided with a plurality of branch 95 tubes 46, which enter a supply of water through the side of the chute or trough, for the purpose of thoroughly washing the sand. The shaft 47 of the pump 42 has fixed thereto a friction pulley 48, and loosely mounted 100 upon said shaft is a friction pulley 50, which is operatively connected to the pulley 12 of the belt 49. The pulley 48 is fixed to rotate with the shaft 47, but capable of sliding thereon, and may be moved axially on the 105 shaft 47 by means of a lever 51, so as to move it into frictional contact with the loose pulley 50, which is belted to the pulley 12. The lever 51 may be held in different adjusted positions by the usual form of hand gripped operated dog 52, in order to hold the lever in different positions. Obviously by increasing the friction between the two pulleys, the faster the pump will operate, and by decreasing the friction between the pulleys, the pump will operate slower, thereby 110 decreasing the supply of water. The faster the pump operates, the greater of supply and force of the water will be forced through the pipe 44, which is provided with a valve 53, for cutting off the water when the occasion arises.

115 The sand to be cleaned is agitated in the sieve, the rock, stone, large pieces being discharged through the openings 16 and passed 120 through the chute 15. The sand which passes through the sieve is carried through the hopper, through the shaft 8, and into the chute 21, where the sand is thoroughly washed, the sand being propelled upwardly 130

through the chute and discharged at its upper end into a wagon, while the foreign matter, refuse, or dirt together with the water travels downwardly and discharges 5 upon the ground.

The screw conveyor shaft 29^a in Figure 6 has a screw conveyor blade 29^b mounted thereon. This spiral or screw blade 29^a comprises a plurality of sections 30^a, which may 10 be casted with the shaft if desired, there being a rectangular shank 20^b passing through the shaft to prevent the section from turning, there being a nut 30^c threaded on a reduced extension 30^d of the shank 30^b, to hold 15 the section in position.

The invention having been set forth, what is claimed as being useful is:

1. In a machine for the purpose indicated, a frame, a driven shaft mounted therein, a 20 chute mounted on the shaft pivotally for tilting movements radially from the shaft, a screw conveyor mounted for operation axially in said chute and being operatively connected to the shaft, whereby material discharged in the chute may be conveyed upwardly and discharged at the upper end of the chute, means for supplying water to the chute accessively throughout its 25 length, whereby the sand is propelled upwardly against the water, and the water, dirt, and trash are carried downwardly and discharged at its lower end on the ground, and a separating means including a chute 30 overlying the first chute in alignment therewith for feeding the material into the first chute.

2. In a machine for the purpose indicated, a frame, a conveyor mounted on the frame for tilting movement vertically and adapted 40 to receive a bath for the sand, a sand elevating element for the conveyor, a separating mechanism mounted on the frame for oscillatory movement and having a chute overlying the conveyor to discharge the sand 45 into the pivoted end of the conveyor and in alignment therewith, a unitary means operatively connecting with the separating means and the elevating element for operating them simultaneously.

50 3. In a machine for the purpose indicated, a frame, a driven shaft mounted in bearings thereof, a conveyor chute pivotally mounted

upon the shaft for tilting movement radially from the shaft, an elevator element mounted in the chute being operatively 55 geared to the driven shaft, means upon the shaft to prevent movement of the chute axially with the shaft, thereby holding the elevator element relatively to its operative gear connections, means to supply a bath to the sand therein, means overlying the chute and in alignment therewith for holding the chute in different adjusted positions, and means for feeding sand to the lower end of the chute. 60 65

4. In a machine for the purpose indicated, a base, a driven shaft, a conveyor chute mounted on said shaft for tilting movement in a plane longitudinally of the base, an elevator element in said chute and operatively 70 connecting with the driven shaft, and vibrating sand supplying means mounted upon the sides of the base for oscillatory movement and having a spout overlying the lower pivoted end of the chute in a direction 75 longitudinally therewith, means for tilting the chute with respect to the spout, whereby the sand may deliver into the lower end of the chute while the supplying means oscillates, means supplying a bath to the sand 80 in the chute, and unitary means operatively connecting with the element and the sand supplying means for operating them both.

5. In a machine for the purpose indicated, a frame, a driven shaft mounted therein, a conveyor mounted pivotally on said shaft for swinging movement radially therefrom, a sand screw elevating element mounted in bearings of the conveyor and lying longitudinally therein and being operatively 90 geared at one end to the driven shaft, means on the driven shaft to prevent axial movement of the conveyor relatively to the shaft to insure maintaining the operative gear connections, an upright support, and a drum 95 having a cable operatively connecting with the support and in turn connected to the conveyor, for tilting the same, and a sand chute overlying the lower pivoted end of the conveyor and disposed in alignment 100 therewith, to discharge sand in the chute.

In testimony whereof I hereunto affix my signature.

WILLIS A. GOODWIN.
